Patented Feb. 3, 1920.

UNITED STATES PATENT OFFICE.

LUDWIG WOLFFGRAM, OF ERIE, PENNSYLVANIA.

ANNEALING-FURNACE.

1,329,873.

Specification of Letters Patent. Patented Feb. 3, 1920.

Application filed May 24, 1918. Serial No. 236,291.

To all whom it may concern:

Be it known that I, LUDWIG WOLFFGRAM, a citizen of the German Empire, and resident of Erie, county of Erie, and State of Pennsylvania, have invented certain new and useful Improvements in Annealing-Furnaces, of which the following is a specification.

The object of my invention is to provide improvements in annealing furnaces for the purpose chiefly of insuring a proper heating of the furnace, and preventing excessive wear thereof, and particularly breakages such as occur frequently with annealing furnaces of the constructions now employed. One of the features of my invention resides in the possibility of employing ordinary firebrick in the construction of the furnace, so that the structure is relatively strong and much less liable to breakage, cracking and other accidents than the existing furnaces of this class.

A typical example of an annealing furnace containing my improvements is represented in the accompanying drawings, in which,

Figure 1 is at the left hand portion a longitudinal section of the improved furnace, taken on line 1-1 of Fig. 3, and at the right hand portion an elevation thereof; and

Figs. 2 and 3 are cross sections taken on lines 2-2 and 3-3 respectively of Fig. 1.

1 designates the centrally located retort or annealing chamber, which as shown is a long horizontal chamber or channel of substantially rectangular cross section, with preferably an arched roof, although I do not wish to restrict myself to this particular shape of the annealing chamber. The interior of said chamber is adapted to receive a supply of air and fuel through transverse channels 1' communicating with flaring mixing tubes 1'' open to the atmosphere as shown in Fig. 3. Into these mixing tubes project the ends of fuel, oil or gas burners 2, provided with valves 2'. The channels 1' preferably extend adjacent to the roof of the annealing chamber 1 in one of the side walls thereof, and widen both vertically and laterally toward said chamber. In the opposite side wall, and preferably adjacent to the bottom of the annealing chamber, I provide a number of outlets 3 which lead into vertical channels 4, the lower ends of which communicate

with horizontal channels 5 extending transversely under the bottom or sole of the annealing chamber 1. The transverse channels 5 communicate at their discharge ends 60 with longitudinal channels 6 which extend adjacent to the bottom wall of the annealing chamber, and under the channels 1'. There are two alining channels 6 which extend from the ends of the furnace to the 65 central portion thereof, the inner ends of said channels being separated by the brick work 6' of the stack connection 7, which latter at its lower end communicates with a longitudinal channel 8 extending the full 70 length of the furnace, at a level below that of the channels 6, and communicating with the opposite ends of the latter by means of vertical connecting channels 9 (see Fig. 1).

Above the roof of the annealing chamber 75 is located a combustion chamber or heating chamber 10 connected with the upper ends of the vertical channels 4, and also connected with transverse channels or flues 11 extending outwardly and connected with 80 flaring mixing tubes 12 similar to the tubes 1''. The channels 11 flare in the same manner as the channels 1'. A gas burner or fuel oil burner 13 is located adjacent to each of the mixing tubes 12, and such burners are provided with controlling valves 13'. The parts 11, 12 and 13 may be arranged directly above the corresponding parts 1', 1'' and 2, or out of vertical alinement therewith. The ends of the annealing chamber 90 1 are closed in any suitable manner, for instance, by doors 14 suspended from chains 14', and movable up and down in any well-known manner. The mixing tubes 1'' and 12 may be provided with sliding dampers 95 1''' and 12' respectively or with other shut-off devices, but I have found that in practice such shut-off devices are not essential, and they may be omitted.

Before bringing the goods to be annealed into the chamber 1, I heat the latter interiorly with a direct flame, by opening the valves 2' and thus burning a mixture of fuel and air in said chamber preferably until the latter is white hot, that is to say, bringing 100 it to a higher temperature than the one obtained subsequently by the indirect or external heating of the annealing chamber. It will be understood that during this preheating, the doors 14 are closed. The combustion gases pass out from the chamber 1 through the channels 3, 4, 5, 6, 9, 8 and 7,

to the stack, and heat the interior of the retort, and also its bottom from below. After the annealing chamber proper has thus been brought to white heat, the burners 2 are shut off by closing their valves 2', the doors 14 are opened, the material to be annealed is introduced, the doors 14 are closed again, and the burners 13 are set in operation to produce combustion of fuel in the upper or 10 roof chamber 10. The combustion gases from this roof chamber flow down in the vertical channels 4 along one of the side walls of the annealing chamber, and then pass under the annealing chamber in the 15 channels 5, and thereupon lengthwise of the furnace in the channels 6, to finally rise in the channel 7 and pass to the stack. It will be seen that the combustion gases journey practically all around the annealing chamber, and therefore keep it heated in a practically uniform manner on all sides. It will also be noted that the combustion gases are caused to journey toward the ends of the furnace as shown best in Fig. 1, and inasmuch as these ends are the parts which are 25 cooled most strongly at the time the doors 14 are opened, the importance of counter-acting this cooling will be understood.

While I have illustrated a preferred and 30 satisfactory form of my invention, it is obvious that changes may be made therein within the spirit and scope thereof, as defined in the appended claims.

I claim:

35 1. A furnace provided with a main chamber, a heating chamber extending over said main chamber and having spaced ports opening through one side of the furnace for the admission of a direct heating agent, said 40 main chamber also having spaced ports opening through the side wall of the furnace for the admission of an independently controllable heating agent, said furnace having a central stack connection, and means 45 for causing a retarded flow of the products of combustion from both of said chambers beneath the main chamber to said stack connection.

2. An annealing furnace provided with a 50 main chamber, an external chamber above the roof of said main chamber, channels extending downwardly from said roof chamber adjacent to one side of said main chamber and communicating with the latter, 55 channels extending transversely under the bottom of the main chamber and communicating with the lower ends of said downward channels, channels communicating

with said transverse channels and extending lengthwise toward the ends of the main 60 chamber, a stack connection at the central part of the furnace, and longitudinal channels leading to said stack connection from the opposite ends of the first-named longitudinal channels. 65

3. A furnace provided with a main chamber having a closed roof, a heating chamber independent of said main chamber, extending over the roof thereof and having spaced ports opening through one side of the 70 furnace for the admission of a direct heating agent, a stack connection for the furnace, and circuitous outlet flues in the furnace walls leading to said stack connection, and separate means of communication from 75 each of said chambers to said flues, said circuitous flues being operative to retard the flow of the products of combustion of the stack connection.

4. A furnace provided with a main chamber, an external chamber above the roof of said main chamber, channels extending downwardly from said roof chamber adjacent to one side of the main chamber, a stack connection adjacent to the other side of said 80 chamber, superposed longitudinal channels one of which communicates with the stack connection while the others communicate with the first-named longitudinal channel at opposite ends thereof, and transverse channels extending under the bottom of the main chamber and connecting said second-named longitudinal channels with said downward channels. 85

5. A furnace provided with a main chamber, an external chamber above the roof of said main chamber, channels extending downwardly from said roof chamber adjacent to one side of the main chamber, a stack connection adjacent to the other side of said 90 chamber, superposed longitudinal channels, the lower one of which communicates with the stack connection at the central portion of the furnace and with the upper longitudinal channels at the ends of the furnace, 95 and transverse channels extending under the bottom of the main chamber and connecting said downward channels with the upper longitudinal channels. 100

In testimony that I claim the foregoing 110 as my invention I have signed my name in presence of two subscribing witnesses.

LUDWIG WOLFFGRAM.
